UNITED STATES PATENT OFFICE.

MAXIME O. PARENTEAU, OF SPRINGFIELD, MASSACHUSETTS.

APPARATUS FOR COVERING SHOE-HOOKS WITH PLASTIC MATERIAL.

SPECIFICATION forming part of Letters Patent No. 641,994, dated January 23, 1900.

Application filed August 12, 1898. Serial No. 688,422. (No model.)

To all whom it may concern:

Be it known that I, MAXIME O. PARENTEAU, a citizen of the United States of America, residing in Springfield, in the county of Hampden and State of Massachusetts, have invented new and useful Improvements in Apparatus for Covering Shoe-Hooks with Plastic Material, of which the following is a specification, reference being had to the accompanying drawings and letters of reference marked thereon.

In the drawings like letters of reference indicate like parts.

Figure 1 is a perspective view of the die. Fig. 2 is a like view of the preferred form of sliding plate. Fig. 3 is a sectional view illustrating a modified form of my device. Fig. 4 is a perspective view of the receiving-plate, which shows hooks in a portion of the receiving-opening. Fig. 5 is a perspective view of the pin-plate. Fig. 6 is a side elevation, in section, of the receiving-plate and pin-plate with hooks mounted upon the pins. Fig. 7 is a perspective view of the receiving-plate with sliding plate in position thereon and with shoe-hooks in the recesses and before the sliding plate has been moved to the position occupied by it while the plastic material is being applied. Fig. 8 is a like view after the sliding plate has been moved to the position occupied by it while the plastic material is being applied. Fig. 9 is an elevation in section showing the receiving-plate, sliding plate, and die all in their proper relative position and with hooks in position to receive the plastic covering; and Fig. 10 is a side view of a hook provided with a shoulder or lug to support the head while the plastic material is being forced upon and around the same.

In detail, *a* indicates the die; *b*, the sliding plate; *c*, the receiving-plate, and *d* the pin-plate.

The object of my invention is to provide an improved apparatus whereby hooks for shoes may be readily handled and placed in position and the heads covered with plastic material and wherein the string-receiving recess in the hook is protected and the plastic material prevented from being forced into the string-receiving opening.

I accomplish the objects of my invention by the means herein shown.

The die *a* is constructed with recesses of the desired form to shape the plastic material upon the top or head of the hook. The 55 receiving-plate *c* is provided with a series of openings of a size to receive the shank of the hook and with enlargements to receive the lower portion of the body of the hook. A sliding plate *b* is provided, which is suitably 60 mounted upon the receiving-plate *c*, preferably by being provided with overhanging sides, as illustrated in Fig. 2. The openings in the sliding plate are of sufficient size to allow the hooks to pass through. The thickness of 65 the sliding plate is just sufficient to fill the string-receiving opening in the hooks.

It will now be seen that if the sliding plate be so adjusted with reference to the receiving-plate as to cause the openings in it to 70 register with the opening in the receiving-plate the hooks may be placed in position, and if after they are so placed the sliding plate is moved in one direction it will pass into the string-receiving openings and fill 75 them, thus occupying the position as illustrated in Fig. 8, and if the die be then placed in position, with the plastic material between said die and the upper surfaces of the hooks, and suitable heat and pressure be applied in 80 the well-known manner the tops or heads of the hooks will be covered by the plastic material and the sliding plate will prevent the plastic material from being forced into the string-receiving openings, and thereby the 85 objectionable feature heretofore obtaining will be avoided.

The hooks may be gathered in any convenient manner. I find, however, that if a quantity of hooks be placed upon the receiving-plate, either with or without the sliding plate being in position, and the plate be gently shaken a large proportion of them will enter the openings and assume an upright position therein, the position being in all respects 95 that desired for the purposes of covering, excepting that they will not all project in the same direction. To overcome this tendency, I find that by moving the sliding plate back and forward several times the hooks will be 100 turned to the desired position, thus allowing the sliding plate to be moved to the position shown in Fig. 8. If, however, it is desired to hasten the operation, I then employ the

- pin-plate *d*, it being provided with pins which register with the openings in the receiving-plate, the pins, however, being all of a length to project through the receiving-plate and lift the hooks, so that they are wholly supported by the pins. Then if the pin-plate and receiving-plate be tilted at an angle and the plates in this position be gently shaken or rapped all the hooks will turn so as to project with their overhanging parts in one direction. The receiving-plate may then be lifted from the pin-plate, thus allowing the hooks to rest in the recess in the receiving-plate, and the sliding plate is moved to the position to protect the string-receiving openings, the covering material preferably consisting of disks of celluloid of the proper size placed in position, die adjusted, and the whole subjected to heat and pressure.
- 20 In the event of it being desired to cause the plastic material to cover and run under the edges of the top of the hook I may form the hooks with a suitable shoulder on the head to support it or employ the pin-plate to support the head. In this event openings would be formed in the sliding plate to permit the pins to pass through and bear against the lower face of the head of the hook. This modification is shown in Fig. 3, in which the pins 25 of the plate *d'* pass through the receiving-plate *c'*, the sliding plate *b'*, and beneath the heads of the hooks to slightly raise them from said sliding plate. The die *a'* is also shown in place in this view.
- 30 In order to maintain the parts in accurate registry while under pressure, I prefer that the receiving-plate and sliding plate be provided with registering pin-receiving openings and the die be provided with pins *e* to 35 register therewith, the openings in the slid-

ing plate being of course so located as to register with the like opening in the receiving-plate when the plates are in position to receive the die.

Having therefore described my invention, 45 what I claim, and desire to secure by Letters Patent, is—

1. The combination of a receiving-plate and a plate arranged to slide thereon provided with a series of complete openings, or openings that are wholly within said sliding plate, substantially as shown. 50

2. The combination of a receiving-plate having openings to receive the shoe-hooks and a pin-plate having pins to enter said openings 55 and bear against and raise the hooks, substantially as shown.

3. The combination of a receiving-plate having openings to receive the hooks, a sliding plate having complete holes or holes 60 wholly within said sliding plate to slide on the receiving-plate and fill the lace-openings in the hooks, a die above said last-mentioned plate and means to hold the whole in registry, substantially as shown. 65

4. The combination of a receiving-plate, a sliding plate mounted thereon to fill the string-receiving openings in the hooks and provided with complete openings or openings wholly within said sliding plate, other holes 70 or openings to permit the passage of pins when in position to close the string-receiving openings, a die, and pin-plate having pins to pass through the receiving-plate and sliding plate and bear against the lower face of 75 the hook-head.

MAXIME O. PARENTEAU.
